UNITED STATES PATENT OFFICE.

THOMAS J. NORTH, OF LOUISVILLE, KENTUCKY.

TROUSERS SUPPORTER.

Application filed October 25, 1922. Serial No. 596,787.

To all whom it may concern:

Be it known that I, THOMAS J. NORTH, a citizen of the United States, and resident of Louisville, in the county of Jefferson and 5 State of Kentucky, have invented certain new and useful Improvements in Trousers Supporters, of which the following is a full, clear, and exact description.

My invention relates to means for supporting trousers, and has for its object to provide such a device which may be attached to the inner side of underwear, trousers and the like adjacent the top thereof and which will draw the trousers tightly around the 15 waist of the wearer.

Another object of the invention is the provision of such a device which may be attached to the usual suspender buttons found on the inner side of trousers, or which may 20 be attached to any other part of the trousers desired.

A further object of the invention is the provision of a buckle which may be used in conjunction with the trousers support and 25 which is so constructed as to eliminate any chance of the prongs injuring the person of the wearer.

Other objects and advantages of the invention will be apparent from the following 30 description when taken in connection with the accompanying drawing, in which:

Figure 1 is a plan view of the device.

Figure 2 is a perspective view of the buckle detached from the supporter.

Figure 3 is an enlarged fragmentary perspective view of the elastic member detached from the buckle.

Figure 4 is a perspective view of the upper portion of a pair of trousers with my 40 complete device attached thereto, and

Figure 5 is a fragmentary plan view of a pair of trousers with the device attached to the suspender buttons.

Referring to the drawing more in detail, 45 the numeral 1 designates an elastic band to which are secured the hooks 2. The band 1 is doubled over one of the hooks 2 and is provided with the usual clip 3 for adjusting the length of the band.

The elastic band 1 is intended to be attached to the interior of the trousers, either front, rear or side, for the purpose of drawing the trousers snugly around the waist of the wearer, and to this end I have provided 55 a pair of buckles which are adapted to be

attached to the trousers at spaced intervals. The buckle is illustrated most clearly in Figure 2 and comprises a frame 4, to which is pivoted the spaced, parallel prongs 5. These prongs 5 are passed into the material of the trousers, and, in order that the same may be held against injury to the person, I have provided the keeper 6, which is pivoted at 7 to the frame 4. The keeper 6 may be provided with the fingers 8 for engaging the prongs 5, if desired.

Extending beyond the pivot 7 of the keeper 6 is a pair of arms 9. These arms 9 are engaged by the band 1 when the latter is drawn taut and thereby holds the keeper 70 against the prongs 5 and substantially parallel with the frame member 4.

In attaching the band 1 to the buckles 4, the hooks of the band are first passed over the bar 10 and then engaged over the 75 end of the frame.

Also pivoted to the band 1 are the button clasps 11. Where desirable, these clasps 11 may be attached to the suspender buttons, as indicated in Figure 5, and when so used 80 the buckles 5 may be detached from the hooks 2.

In operation the prongs 5 of each of the buckles are passed through the material of the trousers at suitable points. The prongs 5 and frame 4 are then moved on their pivot until substantially parallel; the keeper 6 is then swung on its pivot 7 and held in place by engagement of the band 1 with the arms 9. If found desirable, the buckles 90 4 may remain attached to the trousers and the band may be detached at the proper time by merely disengaging the hooks 2 from the buckles. Under some circumstances it may be preferred to use the clasps 11 instead of the buckles 4, and it is then only necessary to disengage the hooks from the buckles and then engage the clasps 11 over the suspender buttons.

From the foregoing description it will be 100 seen that I have provided a very simple and inexpensive device for supporting trousers and also one which is reliable in operation and practically impossible to become accidentally detached.

In accordance with the patent statutes, I have described what I now believe to be the best embodiment of the invention, but I do not wish to be understood thereby as limiting myself or the scope of the inven- 110

tion, as many changes and modifications may be made without departing from the spirit of the invention; all such I aim to include in the scope of the appended claims.

5. What I claim as new and desire to secure by Letters Patent is:

1. A buckle, including a frame member, a pair of prongs pivoted to one end of said frame member, a keeper pivoted to the opposite end of the frame member, and means carried by said keeper and adapted to be en-

gaged by a belt or the like for holding the keeper in contact with the prongs.

2. A buckle, including a frame member, a pair of prongs pivoted to one end of said frame member, a keeper pivoted to the opposite end of the frame member, and a pair of extensions on said keeper adapted to be engaged by a belt or the like for holding the keeper in contact with the prongs. 15

THOS. J. NORTH.
